UNITED STATES PATENT OFFICE.

STEPHEN A. NOLEN, OF SEARCY, ARK., ASSIGNOR OF TWO-THIRDS OF HIS
RIGHT TO JAMES A. HUFF AND JOHN M. HUFF, ONE-THIRD TO EACH.

STRAP FOR WAGON-BODIES.

SPECIFICATION forming part of Letters Patent No. 232,841, dated October 5, 1880.

Application filed July 27, 1880. (No model.)

To all whom it may concern:

Be it known that I, STEPHEN A. NOLEN, of Searcy, in the county of White and State of Arkansas, have invented new and useful Improvements in Flanged Box-Straps for Wagon-Bodies, of which the following is a full, clear, and exact description, reference being had to the accompanying drawings, in which—

Figure 1 represents a perspective view of a wagon-body having my improved box-straps. Fig. 2 represents a detached view in perspective of the box-strap. Fig. 3 is a front view of the same. Fig. 4 is a front view of the box-strap, with a removable bolt for fastening. Fig. 5 is a modification of the same. Fig. 6 is one of the box-straps made for the top frame of the wagon-body.

This invention relates, mainly, to flanged box-straps, by means of which the sides, ends, and bottom of wagon-boxes are secured together. Heretofore box-straps of this nature have been made with their sides parallel throughout their length, and in one piece with a bolt forming their lower end, the latter being screw-threaded to receive a nut. They form an efficient fastening to unite the main parts of a wagon; but if any of them break from rough usage or accidents the damage cannot be conveniently repaired by farmers, wagon-ers, or even ordinary blacksmiths.

The object of my invention is to so contract the area between the sides of the box-strap, near the lower end thereof, as to form an abutment for the head of an ordinary bolt to rest upon, said bolt being used as the main fastening or additional fastening in securing the box-strap to the bottom or cross-bars of a wagon.

My invention consists in a flanged box-strap having its internal area contracted at the lower end thereof, and also in the combination of said box-strap contracted at its lower end with a removable bolt entering said contracted portion.

In the drawings, A represents the bottom of the wagon, which may be made of a series of boards united by cross-bars a.

B represents the sides, and C the ends, of the wagon. These parts are united by four

box-straps, D, having flanges d and a back, d', said back having perforations e to receive screws or rivets, by which the box-straps are secured to the sides of the wagon. The flanges d are parallel nearly the whole length. Only the bottom part of each is made converging toward the other to reduce its internal area and form shoulders d'', between which the body of an ordinary bolt, f, can pass, the head f' thereof resting upon said shoulders.

The back d' of the box-strap can have its lower end extended, as shown in Figs. 2 and 3, in the form of a screw-threaded bolt, d'', and said bolt, passing through the bottom of the wagon and through the cross-bars a, receives a nut, g, that retains the bottom securely united to the sides.

The contracted portion of the box-strap, being at its lower extremity, does not interfere with the reception of the wagon ends C, as the latter can be notched or rounded to fit between the flanges of the box-strap.

The independent bolt f may be used at the same time with the bolt d''; but it is intended mainly for use with the body of the box-strap when the bolt d'' has become broken.

When the box-strap is constructed as shown in Figs. 4 and 5—that is, without any bolt d''—it is less costly than with said bolt. As the box-straps are generally made of cast-iron, it is very trying to screw-cutting tools to remove the sandy and hard skin of the castiron while cutting the thread, always harder than when screw-cutting ordinary wrought-iron rods.

The body of the wagon in Fig. 1 is shown as having a removable top-frame composed of two side-boards, B', and end pieces, C', united by short pieces E, of trough-iron. To prevent these side-boards from spreading apart, they are united at the front and rear by screw-rods H and hand-nuts I. The side-boards of the main body of the wagon are united with similar screw-rods and nuts.

To retain the top-frame in place, it is provided with flat metal straps b, riveted thereto and extending down below the bottom edge of said top-frame, and metal strap-holders b' are secured to the side-boards of the wagon to receive said straps. To keep these parts securely

united, screw-bolts m pass through the central portion of the strap-holders b' and through the straps b , each screw-bolt m being provided with an eccentric handle, m' , to facilitate their attachment and add to their stability.

The tail-board or end C of the wagon extends upward sufficiently to allow its upper corners to enter the trough-iron pieces E of the top-frame, and thus unite together the two boards forming the end of both the main body and top-frame of the wagon.

Having now fully described my invention, I claim—

1. In combination with the body of a wagon,

a flanged box-strap having its internal area 15 contracted at the lower end, substantially as and for the purpose described.

2. The combination, with the body of a wagon, of a flanged box-strap having its internal area contracted at the lower end to form 20 internal shoulders, and a removable bolt entering said contracted portion, substantially as and for the purpose described.

STEPHEN A. NOLEN.
